DEPTH OF DIP CONTROL APPARATUS

Russell A. Tarlton, Kenton, Ohio, assignor to
Westinghouse Electric Corporation, East Pitts-
burgh, Pa., a corporation of Pennsylvania

Application November 21, 1947, Serial No. 787,421

13 Claims. (Cl. 91—46)

1

This invention relates to apparatus for immersing articles in a liquid and, more particularly, to apparatus for controlling the depth to which articles are immersed in a liquid in such manner that the immersion is regulated in accordance with the size of the article and articles of various sizes are immersed to the same depth.

More specifically, this invention relates to apparatus for immersing electrical structures, such as the stator structures employed in electric motors, in a bath of insulating varnish to impregnate the electrical windings on such structures with varnish and to provide the entire structure with a coating of insulating varnish. Certain features of the apparatus disclosed in this application are covered in the copending application of R. L. Ruleff and R. A. Tarlton, Serial No. 787,422, filed November 21, 1947 and to which reference is hereby made.

Many electrical articles, such as stator structures, comprise a magnetizable supporting member on which a coil of wire is wound as an electrical energizing winding. The coil or energizing winding is provided with flexible insulated leads by which an electrical connection to the winding may be made. According to the above-mentioned copending application, such structures are placed on supports carried by a conveyor chain and impregnated and coated with varnish by immersion or dipping in a bath of insulating varnish. The dipping of the articles is accomplished in a continuous manner as they are carried past the varnish dipping station by the conveyor chain. The immersion may be accomplished by moving the article into the dip tank or by moving the dip tank with respect to the article, the latter being the preferred method.

Although it is necessary that the electrical structure be impregnated and coated with varnish, the application of a coating of varnish to the flexible leads is to be avoided. Such a coating causes the leads to become brittle and subject to damage by bending. In order to prevent coating of the flexible leads with varnish, one of the principal objects of this invention is to provide apparatus by which the depth to which the electrical articles are immersed in varnish is controlled so that as little as possible of the leads are immersed. To this end, there is provided a hydraulic motor for moving a varnish containing dip tank toward and away from the article to effect its immersion in and withdrawal from the varnish. A photoelectric cell and timing device so regulates the operation of the hydraulic motor that the article is immersed to

2

a predetermined depth below the level of the varnish in the dip tank. In this manner, all of the article is immersed and only a short length of the flexible lead is coated with varnish. In addition, the control of dipping is accomplished in such manner that articles of different sizes may be fed successively to the dipping station and compensation for the varying article sizes will be made automatically.

10 Another object of this invention is to provide a liquid containing tank with a liquid recirculating system by which the level of liquid in the tank is maintained together with apparatus for controlling the depth to which an article is immersed in the tank.

15 Another object of the invention is to provide a novel arrangement of apparatus for moving a receptacle containing liquid toward and away from a supporting member to immerse articles carried by the supporting member.

20 A still further object of this invention is to provide a photoelectric light sensitive device disposed in the path of relative movement between an article and dip tank as a dipping operation is being performed which is effective to measure the size of the article and initiate control mechanism for stopping the relative movement at a predetermined point, the point of stopping being thus varied automatically with the size of the article.

25 Other objects and advantages will become apparent from the following description:

30 In the drawings, there is shown a preferred embodiment of the invention. In this showing:

35 Figure 1 is an elevational view of a dipping station for immersing articles carried thereto by a conveyor chain;

40 Fig. 2 is an enlarged side view of a portion of the apparatus shown in Figure 1, taken from the right of Figure 1, and particularly illustrating the arrangement of the liquid containing receptacle and elevating mechanism therefor;

45 Fig. 3 is a top plan view of the apparatus shown in Figure 1; and

50 Fig. 4 is a diagrammatic sketch of a control system employed in connection with the apparatus shown in Figure 1.

55 Referring to Figure 1 there is shown a monorail conveyor chain 1 mounted for movement on a rail 2 by rollers 3. The conveyor chain is provided with supports 4 for articles 5 at equally spaced intervals thereon. The particular form of articles 5 shown in the drawings for which the system of this invention has been specifically devised are stators for electric motors and com-

prise cylindrical shells having energizing windings 6 provided on their inner surfaces, as best shown in Figs. 2 and 3, in accordance with conventional practice. The stators 5 are mounted on the supports 4 in such manner that the flexible leads 7 to the windings 6 project upwardly, as best shown in Figs. 1 and 2.

As each support 4 moves into an operative dipping position with respect to a liquid containing receptacle or tank 20, a limit switch 21 is operated to stop the conveyor chain 1. The particular system illustrated is for the purpose of impregnating and coating electrical articles, such as stator windings, with varnish and in such system the liquid contained in the tank 20 is an insulating varnish. In the drawings the limit switch 21 is shown as being operated by the rollers 3 which support the conveyor chain 1. When the conveyor chain is stopped by the limit switch 21, mechanism is operated to raise the tank 20 vertically, as viewed in Fig. 1, to a position in which the articles or stators 5, which have stopped in an operative dipping position with respect to the tank 20, are immersed in the varnish contained in the tank 20. The stators are immersed in the varnish for a predetermined period of time after which the tank 20 is lowered to the position shown in Fig. 1 and the conveyor chain 1 is then started again to move the next support 4 and stator carried thereby into an operative dipping position and to move the support 4 carrying the stators which have just been dipped to a draining position above a drain pan 22 which collects the varnish dripping from the stators 5. These operations are carried out in a continuous step-by-step or intermittent manner and require a predetermined amount of time between intermittent operations of the chain 1. The time required by the dipping operations provides a control feature which is covered and completely set forth in the copending application mentioned above.

Varnish is continuously circulated through the dip tank 20 from a reservoir 23 by a pump 24 which operates to deliver varnish to the tank 20 through a flexible supply conduit 25. Overflow chambers at the ends of the dip tank 20 are connected with flexible exhaust conduits 26 to a main return conduit 27 by which excess varnish is returned by gravity to the reservoir 23. The drip pan 22, as shown in Fig. 1, is also connected to the return conduit 27 so that varnish dripping from the stators 5 is also returned to the reservoir 23. Water cooled heat exchangers 28 are provided on the supply and exhaust conduits 25 and 27 in order to maintain the varnish supplied to the tank 20 at a predetermined temperature.

Referring to Figs. 2 and 3, it will be noted that each support 4 is provided with oppositely projecting arms 29 having forks 30 on the ends thereof, by which each support 4 is adapted to carry two stators 5. The projecting arms 29 are aligned with each other and occupy a position angularly inclined with respect to the path of movement of the chain 1, as best shown in Fig. 3. The dip tank 20 has its opposite ends 31 and 32 angularly offset from each other in order to accommodate the angular inclination of the arms 29 and the stators 5 carried thereby. In this manner the tank 20 need hold only sufficient varnish to immerse the stators 5 mounted on the arms 29. A central chamber 33 of the dip tank 20 is separated from overflow compartments 34 at each end thereof by overflow weirs 35. Each of the compartments 34 is provided with an exhaust

port 36 at the bottom thereof for connection to the flexible exhaust conduit 26. The central varnish containing chamber 33 is provided with a port 37 at the bottom thereof for connection to the flexible inlet conduit 25.

The arrangement of the overflow chambers 34 and weirs 35 together with the varnish recirculating system provides a very important feature with respect to regulating the depth to which the stators 5 are immersed. By this arrangement, varnish is continuously supplied to the chamber 33 and overflows into the compartment 34. The surface level of varnish in the chamber 33 is thus maintained constant. The overflow feature in addition takes care of that varnish displaced by the stators 5 upon immersion and it will thus be noted that such immersion does not alter the level of varnish in the chamber 33. The surface level of the varnish is determined solely by the upper edges of the weirs 35.

Vertical movement of the varnish tank 20 is guided by channel members 38 which have sliding engagement with the corners of the dip tank 20. Vertical movement of the dip tank 20 is effected by a hydraulic cylinder 39 having a piston (not shown) therein connected to a rod 40 on the upper end of which is mounted the dip tank 20. Conduits 41 and 42 are connected to opposite ends of the hydraulic cylinder 39 and are alternately connected with a fluid supply conduit 43 and exhaust conduit 44 by means of a reversing valve indicated as a whole by the numeral 45, as shown in Fig. 4. A flow regulating valve 46 is mounted in the conduit 42 for controlling the downward movement of the tank 20 in a manner to be described. The fluid supply conduit 43 is connected to a suitable source (not shown) for delivering hydraulic fluid under pressure thereto.

A source of light 49 and a photoelectric cell 50 are mounted on the tank 20, as shown in Fig. 2, for controlling the extent of upward movement of the tank 20 in a manner to be described. A plate 51 is connected to one of the guiding supports 38 and is positioned between the light source 49 and photoelectric cell 50 when the tank 20 is in its lowermost position. The plate 51 is so arranged that the photoelectric cell 50 will be energized by the light source 49 immediately upon clearing the upper edge 52 of the plate 51, if no stators are on the support 4 when the tank 20 is elevated. If a stator 5 is carried by the support 4, such stator will be effective to maintain the photoelectric cell 50 deenergized until the tank 20 has moved the light source 49 sufficiently far to clear the upper edge of the stator 5. At that time, the photoelectric cell will be energized to effect a control function in a manner to be described.

In Fig. 4 the essential parts of the apparatus heretofore described which are necessary to an understanding of the control system have been indicated diagrammatically and like numerals have been applied to similar parts. In this showing the reversing valve 45 comprises a casing 53 having a pair of valve structures 54 and 55 mounted therein and respectively provided with a spring bias by springs 56 to a closed position. Solenoids 57 and 58 are provided for operating the valve structures 54 and 55 against the bias provided by the springs 56. Upon energization of the solenoid 57 the valve structure 54 will operate to connect the conduit 42 with the fluid pressure supply conduit 43 and to connect the conduit 41 with the exhaust conduit 44. This action

will admit fluid under pressure to the lower end of the cylinder 39 and exhaust fluid from the upper end of the cylinder 39 to thereby move the tank 20 in an upward direction. Upon deenergization of the up solenoid 57 and energization of the down solenoid 58, the valve structure 55 will be operated to reverse the pressure connections of the conduits 41 and 42 to effect downward movement of the varnish containing dip tank 20.

The speed of movement of the tank 20 is controlled by the flow regulating valve 46 as mentioned above. The flow regulating valve 46 comprises a casing 59 containing an adjustable ball-check valve 60 and a flapper valve 61, both of which are provided with spring biases to closed positions. Upon connection of the conduit 42 with the source of fluid pressure supply, such pressure will be effective to maintain the ball-check valve 60 closed and to open the flapper valve 61 to thereby provide a substantially direct connection of the lower end of the hydraulic cylinder 39 with the supply conduit 43 and the hydraulic cylinder 39 will operate to move the dip tank 20 upwardly at a maximum speed determined by the pressure of the fluid in the supply conduit 43. Upon connection of the conduit 42 with the exhaust conduit 44 in the lowering movement of the dip tank 20, the fluid leaving the lower end of the cylinder 39 will operate to close the flapper valve 61 and unseat the ball-check valve 60. The ball-check valve 60 provides a restricted connection between the separate parts of the conduit 42 and thereby limits the escape of fluid from the lower end of the cylinder 39 and the downward speed of the dip tank 20. Downward speed of the dip tank 20 may be regulated by operation of an adjusting member 62 to vary the tension of a spring 63 which provides a closing bias for the ball-check valve 60. By adjusting the tension of the spring 63, the pressure required to unseat the ball-check valve 60 will be varied and the rate of flow of fluid through the conduit 42 may be regulated. It will be understood that the showing of the reversing valve 45 and flow regulating valve 46 is diagrammatic for the purposes of this description and that the particular structure shown forms no part per se of this invention. Accordingly, it will be understood that any conventional valve structures may be employed in place of the valves 45 and 46 without departing from the principles of this invention.

The control system illustrated in Fig. 4 is energized from a pair of alternating-current supply buses 64 and 65 and employs a master timing circuit TM, a dip timing control circuit TD, and an over-travel timing circuit TO which are energized by the supply buses 64 and 65. The timing control devices TO, TD and TM are provided, respectively, with starting relays 66, 67, and 68 and with operating relays 69, 70 and 71. The timing relays are identical in construction and like numerals have been employed to designate like parts thereof. Each of the relays is provided with a vacuum tube 72 having a condenser 73 in its plate circuit, a pair of resistors 74 and 75, and a potentiometer 76 having a slide contact 77 connected in series with the grid of the tube 72 through a timing condenser 80 which has a discharge resistor 78 connected across its terminals. Since the operation of the timing control relays is the same, it will only be necessary to describe the operation of one of the relays for the purpose of this description. Referring

to the over-travel timing relay TO, it will be noted that the cathode of the tube 72 is connected to one of the A. C. buses 64 through the resistor 75 when its starting relay 66 is open. Under this condition, the condenser 80 will charge with the polarity shown, by means of the grid current, to the peak of the voltage between the bus 64 and the slider 77 of the potentiometer 76. When the start relay 66 is energized, contacts 79 will close to connect the cathode of the tube 72 to the other A. C. bus 65. The grid voltage then consists of two parts; namely, the A. C. voltage between the other of the buses 65 and the slider 77 of the potentiometer 76, and the D. C. voltage 15 across the condenser 80. Since the D. C. voltage in the grid circuit, by reason of the charge on the condenser 80, is greater than the A. C. voltage, the tube 72 will not pass current. The D. C. voltage, however, immediately starts to decrease because condenser 80 discharges through resistor 78 and after a predetermined time the tube 72 will pass sufficient current to energize the operating relay 69. The length of time between the energization of the starting relay and 20 the energization of the operating relay of any of the timing circuits TO, TD, or TM can be adjusted by their respective potentiometers 76. The condenser 73 supplies current to the coil of the operating relays on the half cycles when the tubes 72 are not passing current. The starting relays must remain energized for the duration of the time delay to effect operation of the operation relays. Deenergization of the starting relays will cause the operating relays to be deenergized and will reset the timing function or control by recharging the condenser 80. Each of the timing control devices TO, TD and TM is provided with starting contacts 79 under the control of the starting relays 66, 67 and 68, respectively. The operating relay 69 is provided with contacts 81 and 82 and the operating relays 70 and 71 are provided with contacts 83 and 84 respectively. The showing of the timing control devices TM, TD and TO is diagrammatic and it will be understood that any other suitable type of timing device may be employed without departing from the principles of this invention.

The timing control devices TM, TD and TO operate in connection with a plurality of control relays R1, R2, R3, R4, and R5. Control relay R1 controls contacts 85 and 86; control relay R2 controls contacts 87 and 88; control relay R3 controls contacts 89 and 90; control relay R4 controls a contact 91; and control relay R5 controls contacts 92 and 93. Limit switch 21 controls contacts 21A and 21B and is provided with the spring 94 for biasing it to a position maintaining contact 21A closed.

The conveyor chain 1 is driven by gearing 95 operated by an electric motor 96 which is energized from the alternating-current supply buses 64 and 65. The motor 96 is provided with a solenoid operated brake 97 having a spring 98 for biasing it to an operative braking position whenever its operating coil 99 is deenergized.

In the operation of the control scheme shown in Fig. 5, limit switch contact 21A will be closed when the conveyor chain is being driven from the motor 96 through the gearing 95. With the limit switch 21A closed, relay R1 will be energized and contact 85 will be closed, completing a circuit to the motor 96 and to the operating coil 99 of the solenoid brake 97 to thereby maintain the brake in inoperative position against the bias provided by the spring 98. Upon movement of one of the

supports 4 into an operative dipping position with respect to the dip tank 20, one of the rollers 3 will operate the limit switch 21 against its bias provided by the spring 94 to open the contact 21A and close the contact 21B. Opening of contact 21A will deenergize relay R1 to open contact 85 and close contact 86. Opening of contact 85 will deenergize the motor 96 and operate the brake 97 by deenergizing its operating coil 99. The conveyor chain will thus stop in the position shown in Fig. 5 with one of the supports 4 carrying stators 5 in an operative dipping position with respect to the dip tank 20. A single-pole double-throw switch 100 is provided for energizing the relay R1 to effect operation of the conveyor chain 1 continuously and without its operation being subject to operation of the limit switch 21.

When limit switch 21 operates to open contact 21A to stop movement of the conveyor chain 1, it also operates to close limit switch contact 21B. Closure of limit switch 21B energizes starting relay 68 to start the timing operation of the master timer TM. After a predetermined time, relay 71 of the timer TM will operate to close contact 84 for a purpose to be described. At the same time relay 68 is energized, relay R4 is energized to close contact 91.

It will be recalled that contact 86 closed when relay R1 was deenergized. Closure of contact 86 completes a circuit for energizing the up control valve solenoid 57 through the normally closed contact 82, of the timer TO, normally closed contact 88 of relay R2, closed contact 86 of relay R1, and the switch 100. Energization of the solenoid 87 operates the valve structure 54 to admit fluid under pressure to the lower end of the hydraulic cylinder 39 to raise the dip tank 20 as described above. As the dip tank 20 is elevated, it carries with it the light source 49 and photoelectric tube 50 as described above. When the light source 20 is raised to a position above the stator 5, the photocell 50 will be energized to apply a positive bias to the grid of a control tube 102. The tube 102 will then be rendered conductive and will energize a relay 103 to close contact 104. Closure of contact 104 energizes relay R5 to close contacts 92 and 93. Closure of contact 92 sets up a holding circuit for relay R5. Closure of contact 93 energizes the start relay 66 to close contact 79 of the over-travel timer TO. After a predetermined time, the condenser 77 will be discharged to render the tube 72 conductive and to thereby energize operating relay 69 to open contact 82 and close contact 91. Opening of contact 82 will deenergize the up control solenoid 57 to permit closure of the valve structure 54 by the bias of its spring 56 and the supply of fluid pressure will be cut off from the hydraulic cylinder 39 and the upward movement of the dip tank 20 will be stopped.

It will thus be noted that the stopping of the upward movement of the tank 20 is dependent upon operation of the over-travel timing relay TO completing its timing operation and operation of relay 69. It will also be recalled that the timing function of the relay TO is initiated by energization of the photoelectric tube 50. The time delay between the energization of the photoelectric tube 50 and the operation of the relay 69 to stop the upward movement of the tank 20 is so adjusted by the regulation of the position of the slide contact 77 that the tank 20 will travel a predetermined distance after its upper edge clears the upper edge of the winding

5. This predetermined distance is such that the winding 5 will be immersed in the varnish contained in the tank 20 to a predetermined depth which is sufficient to immerse the flexible lead 7 to a depth of about 1 inch. It will thus be seen that the upward movement of the tank 20 is stopped at a predetermined point with respect to the length of the flexible lead 7 immersed in the varnish irrespective of the size of the stator 5 being dipped.

When operating relay 69 of the over-travel timing relay TO operates to open contact 82 and stop the upward movement of the dip tank 20, contact 81 closes to energize start relay 67 15 of the dip timer relay TD. After a predetermined time in which the stator 5 is maintained immersed, operating relay 70 is energized to close contact 83. Closure of contact 83 completes a circuit to energize down solenoid valve 58 through 20 contact 83, contact 86 and switch 100. Energization of solenoid 58 moves the valve structure 55 against the bias of its spring 56 to admit pressure to the upper end of the cylinder 39 through the conduit 41 and to exhaust fluid 25 from the lower end of the cylinder 39 through the conduit 42. The rate of flow of the exhaust fluid through the conduit 42 is controlled by the valve structure 46 to thereby control the speed at which the tank 20 is lowered, as explained 30 above. The regulation of the lowering speed and its purpose is completely described and covered in the copending application mentioned above.

Upon closure of contact 83 to energize the down valve operating solenoid 58, control relay 35 R2 is energized by a circuit through contact 83, contact 86 and switch 100. Energization of relay R2 closes contact 87 and opens contact 88. Closure of contact 87 sets up a holding circuit for the relay R2 through contact 87, jumper 40 lead 111 and contact 91. Opening of contact 88 interrupts the holding circuit for relay R5 through contact 92 and relay R5 is deenergized, and contacts 92 and 93 open. Opening of contact 93 deenergizes starting relay 66 of the over-travel timer TO and relay 69 is thereby deenergized to open contact 81 and close contact 82. Closing of contact 82 does not energize the up valve solenoid 57 at this time by reason of its energizing circuit being open at contact 88. 50 Opening of contact 81 by deenergization of the operating relay 69 of the over-travel timer TO opens the energizing circuit of starting relay 67 of the dip-time control TD and its operating relay 70 is deenergized to open contact 83. Opening of contact 83 does not deenergize the down control valve due to a holding circuit therefor through contact 87 which was closed upon energization of relay R2. It will thus be seen that opening of contact 83 is effective to deenergize starting relays 66 and 67 to thereby reset the timing control devices TO and TD for subsequent cycle of operations.

As lowering movement of the tank 20 is continued by reason of the energization of the down valve operating solenoid 58, the stator 5 immerses from the top of the tank 20 and moves between the source of light 49 and the photoelectric tube 50. The tube 50 will then cease to conduct current and relay 103 will be deenergized to open contact 104.

As the tank 20 approaches its lower position, an operating lever 105 will strike a limit switch 106 to close contact 107. Limit switch 106 is pivotally mounted and is provided with a gravity bias to its open position. It is in the path of

movement of the operating member 105 carried by the tank 20 during both the up and down movements of the tank 20. The lever 105 is connected by a pivot 108 to the tank 20 and is provided with a spring 109 biasing the member 105 to a position against stop pin 110. In the upward movement of the lever 105, the spring 109 is compressed and the member 105 rides over the limit switch 106. In the down movement of the tank 20, pivotal movement of the operating member 105 is prevented by the stop pin 110 and the member 105 will strike the limit switch 106 to effect closure of the contact 107.

Closure of contact 107 energizes relay R3 by completing a circuit through circuit 91, the lead 111, and contact 107. Energization of relay R3 closes contact 89 and contact 98. Closure of contact 89 completes a holding circuit for the relay R3 through contact 89 and contact 91 of relay R4.

Closure of contact 90 by energization of relay R3 is effective to set up an energizing circuit for relay R1 to start up the conveyor system in the event that the master timer TM has completed its timing operation and has operated to close contact 84. It will be recalled that the starting relay 68 of the timer TM was energized when limit switch 21 operated to close contact 21B to stop the conveyor and initiate the elevation of the dip tank 20. The operations described above in connection with the raising and lowering of the dip tank 20 require a certain amount of time which is employed for the purpose of providing a control feature as explained and covered in the above-mentioned application.

Upon completion of the operation of the timer TM and closure of both contacts 84 and 90, relay R1 will be energized to close contact 85 and thereby energize the motor 96 to start the conveyor system. As movement of the chain 1 is continued, the roller 3 will move from the limit switch 21 and its spring 94 will become effective to open contact 21B and close contact 21A. Closure of contact 21A sets up a holding circuit for the relay R1. Opening of contact 21B de-energizes starting relay 68 of the overall timer TM so that its condenser 88 may be recharged for a subsequent timing operation. Deenergization of its starting relay 68 will result in deenergization of its operating relay 71 to open the contact 84 as explained above. Opening of contact 84 will not deenergize the relay R1 to stop the motor 96 because of the energizing circuit set up through contact 21A. Opening of the limit switch contact 21B also deenergizes relay R4 to open contact 91 and thereby deenergize relay R3 to open contacts 90 and 89. Opening of contact 91 by deenergization of relay R4 interrupts the energizing circuit for relay R2 to open contact 87 and close contact 88. Upon deenergization of relays R2, R3 and R4, the control circuit is in condition for a subsequent cycle of operations as described above.

From the foregoing it will be noted that the manner in which the elevating movement of the tank 20 is controlled to immerse an article on one of the supports 4 in varnish provides an effective arrangement by which articles of various sizes may be immersed to a predetermined depth in the liquid contained in a receptacle. Attention is particularly invited to the fact that the structure of the tank 20 and the recirculating system by which the varnish is maintained at a constant level is an important feature in the control of the depth to which the article is im-

mersed. By raising the tank to a predetermined point with respect to the article, the article will be immersed to the point desired. It will also be noted that the photoelectric structure comprising the photo-cell 50 and light source 49 in effect measures the height of the article on the support during the elevation of the tank. During the raising movement, this photoelectric structure moves relatively with respect to the article 5 and is thus operative to initiate the stopping of the relative movement when the article moves out of the range of the photoelectric structure. The point at which the photoelectric structure operates will thus vary directly with the height of the article. Since the movement after operation of the photoelectric structure as controlled by the timer TO is always constant, it will be seen that the movement may be made to stop with the upper edge of the article 5 a predetermined distance below the surface of the fluid in the tank 20. In this manner, immersion of stators in varnish in the tank 20 may be so conducted that only a short length of the flexible leads will be immersed and the apparatus will automatically adjust itself for articles of different sizes.

In the above-described arrangement, the tank 20 and photo-cell 50 are elevated and lowered to effect immersion of the stators 5. However, it is to be understood that the invention is equally applicable where the tank is stationary and the article is moved to effect immersion. In such case, the article would still move relative to the tank 20 and the photo-cell 50, and the photo-cell would be effective to measure the height of the article being immersed.

Since certain changes may be made in the above construction and different embodiments of the invention may be made without departing from the spirit and scope thereof, it is intended that all matter contained in the above description or shown in the accompanying drawing shall be interpreted as illustrative and not in a limiting sense.

I claim as my invention:

1. Apparatus for immersing an article in a liquid comprising a tank containing liquid, a support for the article, power operated mechanism for effecting relative movement between said tank and said support in a first direction to immerse the article and in a second direction opposite to said first direction to withdraw the article, circuit means controlled by said article and operable after relative displacement of said tank and said support through a distance in said first direction corresponding to the height of said article to produce an electrical output, and an electrical control responsive to said electrical output and rendered operative thereby for actuating said mechanism to stop said relative movement in said first direction.

2. Apparatus for immersing an article in a liquid comprising a tank containing liquid, a support for the article, mechanism for moving said tank and support relative to each other in a direction to immerse the article in said liquid, a control device for operating said mechanism to stop said relative movement, and operating means for actuating said control device comprising a first control and a second control, said first control being operative to actuate said second control upon movement of said article through a distance varying with the height of the article on said support, said second control being operative to actuate said control device upon move-

11

ment of said article through a distance constituting the final portion of relative movement in said one direction which is independent of the height of the article on said support.

3. Apparatus as claimed in claim 2 wherein said first control comprises a light sensitive device which is maintained deenergized by said article during the initial portion of its movement and is energized to actuate said second control upon movement of said article out of range thereof, and said second control comprises a timing device which is rendered operative to actuate said control device a predetermined time after actuation thereof by said first control.

4. In apparatus for immersing an article in a liquid, the combination of a liquid receptacle having a liquid recirculating system for maintaining the liquid at a constant level in said receptacle, with a support for said article, means for moving said receptacle and support relative to each other to immerse the article, a light sensitive device which is maintained deenergized by the article on said support during the initial portion of movement for effecting immersion and which is energized by relative movement of the article out of range thereof, and a timing device operated by said light sensitive device for stopping said relative movement a predetermined time after energization of said light sensitive device.

5. In apparatus for immersing an article in a liquid, the combination of a liquid receptacle having a liquid recirculating system for maintaining the liquid at a constant level in said receptacle, with a support for said article, means for moving said receptacle and support relative to each other to immerse the article, a light sensitive device which is energized in response to relative movement of said article with respect thereto, and means operated by said light sensitive device for stopping said relative movement with said article in a predetermined position with respect to the level of liquid in said receptacle.

6. In apparatus for immersing an article in a liquid, the combination of a liquid receptacle having a liquid recirculating system for maintaining the liquid at a constant level in said receptacle, with a support for said article, means for moving said receptacle and support relative to each other to immerse the article, a light sensitive device which is energized in response to relative movement of said article with respect thereto, and a timing device which is operated upon energization of said light sensitive device, said timing device being operable a predetermined time after operation thereof to stop said relative movement with said article in a predetermined position with respect to the level of liquid in said receptacle.

7. In apparatus for immersing an article in a liquid, the combination of a liquid receptacle having a liquid recirculating system for maintaining the liquid at a constant level in said receptacle, with a support for said article, a hydraulic motor for elevating said receptacle to immerse the article, an electrically operated valve for stopping the operation of said motor, a time delay circuit for controlling said electrically operated valve, circuit means responsive to a displacement of said article relative to said receptacle through a distance corresponding to the height of said article for energizing said time delay circuit, said time delay circuit delaying operation of said electrically operated valve until said article is im-

12

mersed to a predetermined depth below the level of said liquid.

8. In apparatus for immersing an article in a liquid, the combination of a liquid receptacle having a liquid recirculating system for maintaining the liquid at a constant level in said receptacle, with a support for said article, a hydraulic motor for elevating said receptacle to immerse the article, a valve for stopping the operation of said motor, a light sensitive device carried by said receptacle which is maintained deenergized by said article during the initial movement of said receptacle to immerse said article and is energized when it is moved out of the range of said article, and means responsive to energization of said light sensitive device for operating said valve.

9. In apparatus for immersing an article in a liquid, the combination of a liquid receptacle having a liquid recirculating system for maintaining the liquid at a constant level in said receptacle, with a support for said article, a hydraulic motor for elevating said receptacle to immerse the article, a valve for stopping the operation of said motor, a light sensitive device carried by said receptacle which is maintained deenergized by said article during the initial movement of said tank to immerse said article and is energized when it is moved out of the range of said article, and a timing device rendered operable upon energization of said light sensitive device for operating said valve a predetermined time after energization of said light sensitive device to stop said receptacle in a position varying with the size of said article and with said article immersed to a predetermined depth with respect to the level of liquid in said receptacle.

10. In apparatus of the character described, the combination comprising a receptacle containing a liquid, a movable conveyor having article supports thereon, a control device responsive to movement of each of said supports into an operative dipping position with respect to said receptacle for stopping the movement of said conveyor, a fluid pressure motor for moving said receptacle toward and away from said conveyor to immerse articles on said supports in said liquid, an up control valve rendered operative upon operation of said control device to operate said motor to move said receptacle toward said conveyor for immersing an article on said support, a light sensitive device carried by said receptacle which is maintained deenergized by said article during initial movement of said receptacle toward said conveyor and is energized by relative movement of said article out of the range thereof, circuit means responsive to the electrical output of said light sensitive device for operating said up valve to stop the movement of said receptacle toward said conveyor, and a down control valve for operating said motor to move said receptacle away from said conveyor.

11. In apparatus of the character described, the combination comprising a receptacle containing a liquid, a movable conveyor having article supports thereon, a control device responsive to movement of each of said supports into an operative dipping position with respect to said receptacle for stopping the movement of said conveyor, a fluid pressure motor for moving said receptacle toward and away from said conveyor to immerse articles on said supports in said liquid, an up control valve rendered operative upon operation of said control device to operate said motor to move said receptacle toward said con-

veyor for immersing an article on said support, a light sensitive device carried by said receptacle which is maintained deenergized by said article during initial movement of said receptacle toward said conveyor and is energized by relative movement of said article out of the range thereof, a time delay device controlled by said light sensitive device, valve control apparatus controlled by said time delay device for operating said up valve to stop the movement of said receptacle towards said conveyor, said time delay device affording a delay in operation of said up valve after energization of said light sensitive device to provide immersion of said article in said liquid to a predetermined depth, and a down control valve for operating said motor to move said receptacle away from said conveyor.

12. In apparatus for immersing an article in a liquid, the combination of, a stationary frame structure, a conveyor mounted for movement on said frame structure, said conveyor having supports thereon each for supporting an article, a receptacle containing a liquid, means mounting said receptacle on said frame structure for movement towards and away from said conveyor for immersing and withdrawing articles from said liquid, motor means for moving said receptacle, a light sensitive device supported on said receptacle above the top thereof, a light source supported on said receptacle at a point thereon removed from said light source in a position above the top of said receptacle to illuminate said light sensitive device, an opaque shield mounted on said frame structure between said light sensitive device and said light source, the upper edge of said shield being higher than the bottom edge of an article supported on one of said supports, means operated by each of said supports upon movement thereof by said conveyor to a position in which the article on said support is over said receptacle for operating said motor means to move said receptacle towards said conveyor, said article shielding said light sensitive device from said light source, and permitting illumination of said light sensitive device by said light source upon elevation of said light sensitive device and light source by said receptacle above the top of said article, and circuit means responsive to said light sensitive device for stopping said motor means.

13. In apparatus for immersing an article in a liquid, the combination of, a stationary frame structure, a conveyor mounted for movement on said frame structure, said conveyor having supports thereon each for supporting an article, a receptacle containing a liquid, means mounting said receptacle on said frame structure for movement towards and away from said conveyor for immersing and withdrawing articles from said liquid, motor means for moving said receptacle, a light sensitive device supported on said receptacle above the top thereof, a light source supported on said receptacle at a point thereon removed from said light source in a position above the top of said receptacle to illuminate said light sensitive device, an opaque shield mounted on said frame structure between said light sensitive device and said light source, the upper edge of said shield being higher than the bottom edge of an article supported on one of said supports, means operated by each of said supports upon movement thereof by said conveyor to a position in which the article on said support is over said receptacle for operating said motor means to move said receptacle towards said conveyor, said article shielding said light sensitive device from said light source, and permitting illumination of said light sensitive device by said light source upon elevation of said light sensitive device and light source by said receptacle above the top of said article, an electrical time delay control device energized by said light sensitive device, said electrical time delay control device having an output which is delayed a predetermined time interval after energization thereof, and control means responsive to the output of said electrical time delay control device for stopping said motor means.
